UNITED STATES PATENT OFFICE.

JOSEPH PERNA, OF PHILADELPHIA, PENNSYLVANIA.

TUNNEL AND TRENCH EXCAVATING SYSTEM.

1,279,148.

Specification of Letters Patent. Patented Sept. 17, 1918.

Application filed October 3, 1914. Serial No. 864,906.

To all whom it may concern:

Be it known that I, JOSEPH PERNA, a citizen of the United States, residing at Philadelphia, in the county of Philadelphia and 5 State of Pennsylvania, have invented new and useful Improvements in Tunnel and Trench Excavating Systems, of which the following is a specification.

My invention relates to new and useful 10 improvements in tunnel and trench excavating systems, and has for its object to provide an exceedingly simple and effective device of this character, whereby the time, labor and expense required in excavating tunnels 15 and trenches may be greatly decreased.

A further object of the invention is to provide a new and useful improvement in carriers which are used in excavating work.

A still further object of the invention is 20 to provide a switch point for use with tracks as generally installed at the present time.

With these ends in view this invention 25 consists in the details of construction and combination of elements hereinafter set forth and then specifically designated by the claim.

In order that those skilled in the art to which this invention appertains may understand how to make and use the same, I will 30 describe its construction in detail, referring by numeral to the accompanying drawing forming a part of this specification, in which—

Figure 1, is a transverse sectional view of 35 a tunnel showing my system installed and illustrating the bucket ready to be withdrawn.

Fig. 2, is a longitudinal sectional view thereof, showing the bucket slightly lowered.

Fig. 3, is a plan view of the track showing 40 the switch point for transferring the carriage from the main track to either of the sidings.

Fig. 4, is a side elevation thereof.

Fig. 5, is an enlarged elevation of the 45 switch point;

Fig. 6, is a plan view thereof; and

Fig. 7, is a perspective view of a section 50 of track, showing a modified form of the means for separating the traveling guides.

In carrying out my invention as here embodied 2 represents a tunnel having uprights 3 therein and cross beams 4 and 5 secured thereto. To the cross beams 4 are secured

the supports 6 arranged in pairs as plainly 55 shown in Fig. 1. Each of the supports comprises a horizontal body portion 7 adapted to engage the top of the cross beams 4, having one end bent downward to form the depending finger 8 which engages one side of 60 the cross beam to prevent the accidental displacement of the support. From the opposite end of the body portion 7 projects a downwardly extending arm 9 from the end 65 of which is formed the hook 10 lying at right angles to the body 7. The hook of each pair of supports engages the upper flange of the track 11 preferably in the form of an I beam, thereby suspending the track from the cross beams 4. 70

12 denotes the hanger comprising side walls 13, each having secured thereto the shafts 14 on which are journaled the wheels 15, said wheels adapted to run upon the lower flange of the I beam track. In the 75 side walls 13 of the hanger is also mounted an axle 16 on which is journaled the grooved wheel or pulley 17 over which operates the hoisting rope 18, one end of said hoisting rope having secured thereto the support 80 connection 19 comprising a link 20 for fastening the connection to the hoisting rope, a supporting link 21 and the hook 22, said hook engaging the link 23 carried by the bail 24 of the dumping bucket 25. The supporting link is of greater width than the link 20, thereby forming shoulders 50 which when the support is drawn upward toward the hanger will engage the transverse rods or bolts 51 carried by the hanger 90 to prevent the support connection from being drawn into the grooved pulley, said rods or bolts also holding the side walls of the hanger together and bracing the same. The side walls 13 of the hanger are provided 95 with elongated openings 26, so that when the bucket is hoisted to bring the supporting link 21 into alinement with the openings 26, a pin 27 may be placed in said openings and through the link 21, thus relieving the hoisting rope 18 of the weight of the bucket and its contents and permitting said hoisting rope to be used for drawing the carrier 100 from the excavation.

I have here described the carrier as being 105 drawn out from the excavation, whether in the form of a tunnel or trench, by means of a hoisting rope and it is to be understood

that either steam, electrical, hydraulic or hand power may be used to operate the same, and if found desirable the hoisting rope may be entirely eliminated, and the carrier be manually pushed from the excavation.

The side walls 13 of the hanger are further provided with holes 28 through which a pin 29 or its equivalent may be passed and then inserted in one of the holes 10 30 in the web of the I-beam track to hold the carrier in any desired position while the bucket is being filled, or a pin may be placed in one of the holes 30, and used as a stop to limit the inward travel of the carrier.

15 The hoisting rope 18 is supported and guided by the traveling guides 31, each mounted upon wheels 32 arranged to run upon the lower flange of the I-beam track, and each having journaled therein another 20 wheel or pulley 33 over which the hoisting rope 18 runs and is prevented from sagging and obstructing the workmen.

Each of the traveling guides are fastened together and to the hanger by chains 34, or 25 their equivalent which properly space said traveling guides as they pass into the excavation, and when the carrier is being withdrawn from the excavation it will engage drawn from the excavation it will engage 30 said traveling guides successively, pushing them out before it.

Where the work being done will permit the suspending of the track at an angle the carrier and the traveling guides will run into the excavation by gravity, but where it is necessary to suspend the track on an approximately horizontal line, I find that it is necessary to draw the carrier into the excavation, and to do so I provide a rope, cable, or its equivalent 35 which is attached 40 to the hanger and runs over a sheave at the inner end of the excavation so that by drawing upon said rope the carrier will be run to the proper position.

In Figs. 3 to 6 I have shown my improved 45 means for transferring the carrier from one track to another, in which 11 represents the main track while 36 and 37 denote two sidings, the ends of the sidings 36 and 37 being spaced from the end of the main track 50 11 and between the adjacent ends is interposed the switch point 38 of the same shape and size as the track and sidings, these being here illustrated as made from I-beams.

One end of the switch point is arcuate or 55 convex in shape as at 39 to correspond with the concave end 40 of the main track 11, and this end of the switch point is supported by a rod 41 which passes through the hole 42 in the upper flange and projects into the cut- 60 away portion or cavity 43 formed in the web, and on the inner end of said rod is mounted a nut 44, said rod pivoting the switch point in its position adjacent the end of the main track 11. The opposite end 65 of the switch point is supported by a me-

tallic strip 45 which passes through a slot 46 in the web of the switch point just below the upper flange, and said metallic strip 45 is supported at its ends in any suitable manner as by the uprights 47.

70 After the carrier is moved along the main track 11 and it is desired to run the same upon one of the sidings 36 and 37 the movable end of the switch point 38 is moved in the desired direction along the metallic strip 45 to bring said switch point in alignment with the desired siding at which time the carrier will proceed along the track in the ordinary manner, passing from the main track 11 over the switch point 38 to the desired siding 80 36 or 37.

In Fig. 7 I have shown a slightly modified form of the means for spacing the different traveling guides as they pass into the excavation, in which I provide each of said 85 traveling guides with projecting arms 38, the length of the arms of each succeeding guide being longer than the preceding one, and these arms are adapted to contact with the inverted U shaped stops 49 carried by 90 the track and placed at suitable intervals, the arms of said U shaped stops being spaced from the track, the one nearest the opening or beginning of the excavation having its arms spaced the greatest distance 95 from the track and each succeeding stop having its arms spaced a less distance from the track, so that as the traveling guides pass into the excavation, the one having the longest projecting arms will contact with 100 the first stop and be held in this position, when the other traveling guides will continue to run along the track until their arms come in contact with their respective stops. By using this form of my improvement it 105 is unnecessary to chain the traveling guides to the carrier, yet they will be stopped at the proper points to hold the rope above the heads of the workmen or out of the way of their tools.

110 Of course I do not wish to be limited to the exact details of construction as here shown, as these may be varied within the limits of the appended claim without departing from the spirit of my invention.

Having thus fully described my invention, what I claim as new and useful, is—

115 In combination, a track, a carrier adapted to travel on said track, said carrier comprising side walls having elongated openings, 120 shafts secured to said side walls, wheels journaled on said shafts, an axle mounted in said side walls, a grooved pulley journaled on said axle and rods secured to said side walls and disposed across the space between said side walls, a hoisting rope passing over said grooved pulley, a support connection secured to said rope consisting of a link, a supporting link and a hook, said supporting link adapted to engage the rods 125 130

for limiting the movement of the hoisting rope relative to the carrier, a bucket carried by said hook and a pin adapted to be inserted through the elongated openings and the supporting link for relieving the hoisting rope of the weight of the bucket.

5 In testimony whereof, I have hereunto

affixed my signature in the presence of two subscribing witnesses.

JOSEPH PERNAS.
